(57) **CLAIM**

The ornamental design for a toy car, as shown and described.

DESCRIPTION

FIG. 1 is a left front perspective view of a toy car showing my new design;

FIG. 2 is a left rear perspective view thereof;

FIG. 3 is a left side elevational view thereof;

FIG. 4 is a right side elevational view thereof;

FIG. 5 is a top plan view thereof;

FIG. 6 is a front elevational view thereof; and,

FIG. 7 is a rear elevational view thereof.

The broken lines illustrate portions of the toy car that form no part of the claimed design.
